Attorney

UNITED STATES PATENT OFFICE.

LORING COES, OF WORCESTER, MASSACHUSETTS.

WRENCH.

SPECIFICATION forming part of Letters Patent No. 229,673, dated July 6, 1880.

Application filed May 17, 1880. (No model.)

To all whom it may concern:

Be it known that I, LORING COES, of Worcester, in the county of Worcester and State of Massachusetts, have invented certain new 5 and useful Improvements in Wrenches; and I declare the following to be a description of my said invention sufficiently full, clear, and exact to enable others skilled in the art to which it appertains to make and use the same, 10 reference being had to the accompanying drawings, which form a part of this specification, and in which—

Figure 1 represents a front view of a screw-wrench constructed in accordance with my invention. Fig. 2 represents a side view of the same, one side of the handle being removed to show the internal construction. Fig. 3 is a perspective view of the bar, shank, and key. Fig. 4 is a transverse section at line *w w*. Fig. 5 is a transverse section at line *x x*. Fig. 6 is a transverse section at line *y y*, and Fig. 7 is a section of the handle-frame only at line *x x*. Fig. 8 is a section of the handle-frame only at the line *z z*.

25 This invention relates to that class of wrenches known as the "Coes screw-wrench;" and it consists in certain improvements in the construction of the handle and bar-shank and the method of combining and attaching said 30 parts together, as hereinafter explained.

In the drawings, *A* denotes the wrench-bar, provided with a head, *B*, and supporting the sliding jaw *C*, operated by the rosette-screw *D*, in ordinary well-known manner, and there- 35 fore requiring no further description herein.

The shank of the bar is made, as shown in Fig. 3, with a reduced portion *A'*, about one-third (more or less) of the thickness of the full bar, flat upon the sides, and having its edges 40 *a*, which are longitudinally parallel, or nearly so, milled off on the arc of a circle, or of cylindrical form, the milled portion being also extended onto the thick part of the bar, as at *c*, for a short distance, forming shoulders *d d* 45 at the front and rear sides, against which the end of the handle abuts. A central longitudinal slot or opening, *f*, is formed through the shank, as shown.

The handle is made with a metal central 50 frame, *E*, to which are fitted wood side plates, *F*, the parts being constructed and arranged

as follows: The upper and lower ends of the metal frame *E* are made the full size or thickness required for the handle, while the intermediate portion is made thinner, and of about 55 the same thickness as the reduced part of the bar-shank, the central portion being open to receive said bar-shank and to lighten the weight of metal. The upper end of the frame *E* is made square to fit against the shoulders 60 *d d* of the bar *A*, and has the usual projection *G* to support the end of the rosette-screw *D*.

Cross plates or bars *H* are rigidly fixed upon the frame *E*, preferably cast integral therewith, and joining its two sides, *e e*, in the manner shown, and the said sides *e e* are formed concave on their inner faces to fit closely to the rounded edges of the bar-shank *A'* throughout the length of the latter. These inner edges are finished by driving a broaching-tool in at 70 the upper end and down to the enlargement at the center of the handle-frame. They are thus made to fit accurately and firmly to the milled edges *a* on the bar-shank *A'*.

A wedge pin or key, *I*, is driven through the 75 opening *f* of the bar-shank at the back of the cross-pieces *H*, which key *I* draws the shoulders *d* firmly against the end of the handle and locks the parts securely in place, so that the bar *A* and handle-frame *E* are as firm and rigid 80 in their connection as if solid or made in a single piece.

The key-seat *i* on the cross-bars *H* is milled out after the top end of the handle-frame is squared off, so that the distance will be uniform on all handles, and the end seats, *m*, for the wood side plates, *F*, may be dressed out 85 with a circular milling-tool, so that all will be alike. The wood side pieces, *F*, which may be turned in pairs on a pattern-lathe and then 90 separated, are fitted to the sides of the metal frame *E*, and are retained in position by the screws or rivets *K*, extending through from side to side, as shown, one passing through the opening *f* of the bar and the other through 95 a hole in the cross-brace of the frame, as illustrated. The exterior of the handle is finished smooth and of an oval form at its ends, so as to project but little on the sides at its junction with the bar *A*, the central portion being 100 nearly round.

The key *I* may be made with rounded or

square bearing-sides, as preferred, and could be arranged through instead of at the back of the cross-pieces H, if desired.

By constructing and arranging the parts in the manner shown and described, a very strong, serviceable, and desirable wrench is produced, which can be manufactured with facility and at a moderate cost.

What I claim as of my invention, and desire to secure by Letters Patent, is—

1. The handle-frame E, provided with cross-pieces H and close-fitting concaved sides e e, in combination with the bar A, having the reduced shank A', with rounded edges a a, shoulders b, and opening f, and the locking-key I, arranged as set forth.

2. The combination, with the bar A, of the within-described handle, composed of the metallic central frame, E, having close-fitted sides e e, with cross-bars H, secured to the bar-shank by the locking-key I, and the wood side plates, F, fitted to said frame for inclosing said key, and secured by the circular end seats, m, and screws K, as shown and described.

Witness my hand this 13th day of May, A. 25 D. 1880.

LORING COES.
